E. C. GLEDHILL.
CAR UNLOADING APPARATUS.
APPLICATION FILED JULY 28, 1914.

1,212,624.

Patented Jan. 16, 1917.

UNITED STATES PATENT OFFICE.

EDWARD C. GLEDHILL, OF GALION, OHIO.

CAR-UNLOADING APPARATUS.

1,212,624.

Specification of Letters Patent. Patented Jan. 16, 1917.

Original application filed March 31, 1914, Serial No. 828,551. Divided and this application filed July 28, 1914. Serial No. 853,699.

To all whom it may concern:

Be it known that I, EDWARD C. GLEDHILL, citizen of the United States, residing at Galion, in the county of Crawford and State 5 of Ohio, have invented certain new and useful Improvements in Car-Unloading Apparatus, of which the following is a specification.

My invention relates to unloading apparatus and this application is a division of an application filed by me March 31, 1914, Serial No. 828,551, the claims herein being confined to a species illustrated and described but not specifically claimed in said 15 application and no claim to the generic invention being made herein.

The drawing is a sectional elevation of an apparatus embodying the present invention.

In carrying out my present invention, I 20 arrange below the railroad track, indicated at 1, a box or hopper 2, which will be of such dimensions that it may fit between two of the railroad ties and extend beyond the side of the track so as to accommodate the 25 lower portion of an endless apron or conveyer. In the top of this box is provided a plurality of openings 3 which may be independently closed or opened by means of sliding covers or doors 4 mounted on the 30 under side of the top of the box. This arrangement permits any one of the openings to be uncovered while retaining all the others in closed condition.

A pocket or boot 41 is carried by the 35 lower end of an elevator frame 5 and is disposed within the receiving box or hopper 2, an elevator consisting of an endless chain of buckets 40 being carried by said frame and operating in said boot or pocket.

40 The shaft 43, which carries the lower roller for the elevator, is equipped with a crank 44 at one end and a pitman 45 is pivoted to the outer end of said crank, the opposite end of said pitman being pivoted to the side of a feed table or box 46 which is hung within the receiving box 2 by means of links 47 and is provided with a series of stepped surfaces 48 on its bottom. The feeding table is disposed with the end more 45 remote from the elevator higher than the end nearer the elevator so that there will be a tendency of the material disposed on the feeding table to gravitate to the elevator. This tendency of the material is increased 50 by the oscillation imparted to the table through the crank 44 and the pitman 45

which will cause the steps 48 to positively feed the material into the pocket or boot 41 from which it will be taken up by the 60 elevator.

The device is preferably portable and is, therefore, mounted on a wheeled truck 22 which may also support a gas engine or other motor for operating the conveyer through a belt 23 and pulley 24. The upper 65 portion of the conveyer frame is supported by standards 25 which are preferably extensible or otherwise adjustable and the lower portion of the said frame is carried by levers 26 fulcrumed on the truck and 70 manipulated by links 27 extending forwardly thereon. The conveyer frame may thus be readily adjusted to any desired inclination and at the upper end of the conveyer is a chute 28 by which the material 75 may be directed into a bin, wagon, or other receptacle.

It is thought the operation and advantages of my improved apparatus will be readily understood from the foregoing description taken in connection with the accompanying drawings. The car to be unloaded is drawn to a point over the receiving box 2 and the material within the car permitted to flow slowly therefrom onto the 85 top of the box. One of the openings 3 in the top of the box is uncovered and the material will then drop through said opening onto the feed table for delivery to the elevator. When all of the material over one 90 of the openings in the receiving box has been taken up by the elevator another opening is uncovered and a second quantity of material will be transferred to the bin or wagon. This operation is repeated until the 95 entire car load of material has been transferred.

The apparatus is exceedingly simple in the construction and arrangement of its parts and will be found highly efficient for 100 the purposes for which it is designed.

The receiving box need not be very large and will be found of sufficient capacity if it be of such width that it may be placed between two of the railroad ties if the same 105 are ordinarily spaced apart.

Having thus described the invention what is claimed as new is:—

1. The combination with a receiving box having its top open at one end and provided 110 with a discharge opening for the passage of material deposited upon said top, of a truck,

- an elevator carried by the truck and having its lower end extending through the open end of the top of the receiving box, a boot carried by the lower end of the elevator, a feeding table having its discharge end positioned above the boot, links forming a pivotal connection between the feeding table and the receiving box, means for driving the elevator, a connection between the elevator and the feeding table for imparting a reciprocating motion to said table, and a connection between the elevator and truck for adjusting the lower end of the elevator longitudinally of the receiving box.
- 10 5. The combination with a receiving box adapted to be positioned beneath a vehicle runway and having its top open at one end and provided with a discharge opening for the passage of material deposited upon said
- 15 15. 2. The combination with a receiving box adapted to be positioned beneath a vehicle runway and having its top open at one end and provided with a discharge opening for the passage of material deposited upon said

top, of an elevator having its lower end extending through the open end of the top and including a shaft, a boot carried by the lower end of the elevator, a feeding table suspended from the top of the receiving box and mounted for reciprocating movement therein, a crank secured to the elevator shaft, a pitman forming a connection between the crank and feeding table, and means connected with the elevator for adjusting said elevator together with the boot and feeding table longitudinally of the receiving box.

In testimony whereof I affix my signature in presence of two witnesses.

EDWARD C. GLEDHILL. [L.S.]
